UNITED STATES PATENT OFFICE.

EDWARD C. WOOD, OF SOMERVILLE, MASSACHUSETTS, ASSIGNOR TO SUBMARINE SIGNAL COMPANY, OF PORTLAND, MAINE, A CORPORATION OF MAINE.

RECEIVER-MOUNTING FOR SUBMARINE SIGNALS.

1,336,497.

Specification of Letters Patent.

Patented Apr. 13, 1920.

Application filed May 18, 1918. Serial No. 235,377.

To all whom it may concern:

Be it known that I, EDWARD C. Wood, of Somerville, in the county of Middlesex and State of Massachusetts, a citizen of the 5 United States, have invented a new and useful Improvement in Receiver-Mountings for Submarine Signals, of which the following is a specification.

A microphone installed on board ship to 10 receive signals or sounds is subject not only to the influence of those sound waves approaching it from outside the ship but also to vibrations originating on shipboard. Thus at the receiving station, say the pilot 15 house, there is apt to be confusion between those sounds which it is intended to receive and those which may be called immaterial, *i. e.*, those which, originating at the receiving station, convey no intelligence to the observer. He is intent on analyzing or receiving 20 sounds or signals from a distance and his work is confused by sounds otherwise originating.

I shall describe my invention with relation 25 to shipboard installation, but I do not mean to limit it thereto as it may be otherwise used. It relates to a mounting of a microphone, such that not only are the undesirable lateral vibrations largely eliminated, but the microphone vibrations are 30 amplified.

My invention will be understood by reference to the drawings in which it is shown in its preferred form;

35 Figure 1 being a horizontal section of a mechanism embodying my invention, and

Fig. 2 a section on line 2—2 of Fig. 1.

A is a plate which may be part of the skin of the ship, preferably a portion of the 40 side thereof, A¹ being the usual ribs. B is a heavy metallic inertia ring which is bolted to the ribs by bolts b. It may be otherwise or additionally attached if thought best. C is a heavy cast iron ring 45 carrying supports c for knife edges d or the like projecting laterally from a reed or other vibrator D. Hence it is convenient to call the ring C an anvil. The supports c, c are preferably threaded and screw into the anvil 50 so as to be adjustable. Between the anvil

C and the ring B is a gasket E preferably a soft rubber ring of such size and character as to serve as an acoustic insulator between the two parts and so reduce to a minimum the communication of vibrations between 55 B, which is attached to the ship, and the parts attached to C as well as C itself. The supports may be flat on their upper surface as shown in one instance or may be grooved as at c¹ or otherwise as thought best. 60

When the apparatus is in position the reed or its equivalent D is attached to the plate A by a wire F, preferably by a screw eye a which is held in place by a set nut a¹, the upper end of the wire being attached 65 to a second screw eye d¹ having a somewhat longer shank, which is held in place by set nuts d², d², the whole being arranged to hold the knife edges d firmly on their seats so that the reed will vibrate in phase with the 70 plate A.

The upper end of the screw eye d¹ holds a core, preferably in the form of a cup, G which as shown is threaded to it and rests against the upper nut d² so that it also vibrates with the reed D, and around this cup, which is preferably made of aluminium, is wound a coil H of insulated wire the ends of which are connected with binding posts h which in turn are connected by wires h¹ 75 80 with a source H¹ of direct current.

The binding posts h are mounted in an inverted U-shaped strap J which is attached by screws j to the anvil C, said binding posts being insulated from the strap J by sleeves 85 and washers j¹ of insulating material.

To the strap J is also attached, though insulated therefrom, one member K of the microphone, the other member K¹ of which is attached by the screws l to a plate L which 90 forms the end of a copper tube L¹ which is of slightly smaller diameter than the cup G so that it may vibrate freely within it, and which forms a secondary to the coil H. The leads k of the microphone are connected 95 to a telephone receiver or other indicator and a source of current in the usual manner. M is a cover bolted to the ring B with a rubber gasket in it to make it watertight.

In practice compressional waves actuate 100

the plate A and its vibration actuates the reed D which is preferably tuned, and the cup G, and sets in vibration the coil H through the instrumentality of the cup G around which the coil H is tightly wound. The coil H produces a magnetic flux which acts upon the copper tube L¹ causing it to vibrate and energize the microphone.

The instrument should be highly efficient as it will not be affected by lateral vibrations or any other vibrations than those substantially normal to the plate A, but to this end the attachment should be absolutely rigid. While the efficiency of the couple between H and K¹ may be low, there is a considerable gain in the couples between A and D and hence the efficiency of the apparatus as a whole will give extremely good results.

It is believed that an apparatus of this character is absolutely new and hence I do not mean to confine myself to the exact embodiment of my invention shown in the drawings and above described.

What I claim as my invention is:—

1. The indicator mounting above described comprising a compressional wave-receiving member, a vibrating member connected thereto, an indicator, a transformer one member of which is connected to said vibrating member, the other member being mounted to vibrate and connected to said indicator, and connections whereby one member of said transformer may be electrically energized.

2. The microphone mounting above described comprising a compressional wave receiving member, a vibrating member connected thereto and acoustically insulated therefrom, a direct current circuit operatively mounted on said vibrating member and comprising a coil, a secondary mounted to vibrate located within said coil, and a microphone and its connections, one member of said microphone being mechanically connected to said secondary to vibrate therewith.

3. The microphone mounting above described comprising a compressional wave receiving member, a vibrating member connected thereto, a core mounted on said vibrating member, a coil wound around said core and forming part of a direct current circuit, a secondary mounted to vibrate located within said coil, and a microphone and its connections, one member of said microphone being mechanically connected to said secondary to vibrate therewith.

4. The microphone mounting above described comprising a compressional wave receiving member, a vibrating member connected thereto, a core of magnetic material mounted on said vibrating member, a coil forming part of a direct current circuit and adapted to move with said core, a secondary

mounted to vibrate located within said coil, and a microphone and its connections, one member of said microphone being mechanically connected to said secondary to vibrate therewith.

5. The microphone mounting above described comprising a compressional wave receiving member, a vibrating member connected thereto and acoustically insulated therefrom, a core mounted on said vibrating member, a coil wound around said core and forming part of a direct current circuit, a secondary mounted to vibrate located within said coil, and a microphone and its connections, one member of said microphone being mechanically connected to said secondary to vibrate therewith.

6. The microphone mounting above described comprising a compressional wave receiving member, a vibrating member connected thereto and acoustically insulated therefrom, a core of magnetic material mounted on said vibrating member, a coil forming part of a direct current circuit and adapted to move with said core, a secondary mounted to vibrate located within said coil, and a microphone and its connections, one member of said microphone being mechanically connected to said secondary to vibrate therewith.

7. In a device of the kind described, a compressional wave receiving member, a vibrating member and a microphone one member of which is connected to said vibrating member, and means for connecting said receiving member and said vibrating member comprising an anvil, an acoustic insulator located between said anvil and said receiving member, said anvil being provided with means to support said vibrating member at nodal points and said vibrating member being attached to said receiving member to be vibrated thereby.

8. In a device of the kind described, a compressional wave receiving member, a vibrating member and a microphone one member of which is connected to said vibrating member, and means for connecting said receiving member and said vibrating member comprising an anvil, an acoustic insulator located between said anvil and said receiving member, said anvil being provided with means to support said vibrating member at nodal points and said vibrating member being attached to said receiving member to be vibrated thereby, said anvil and said receiving member being acoustically insulated from each other.

9. A microphone mounting comprising a receiving member, an inertia member connected thereto, an anvil, means located between said anvil and said inertia member whereby the vibrations of said inertia member will be insulated from said anvil, and a microphone one member of which is con-

nected to said receiving member and said anvil.

10. That method of receiving at an indicator compressional waves coming from a 5 desired direction, which consists in causing one member of a transformer to be vibrated by said waves in a line parallel with said

direction, whereby the electrical energy due to the transformer action may be collected on an indicator, and absorbing the vibrations of other compressional waves before they reach the transformer. 10

EDWARD C. WOOD.
